SKIRT BLOCKER

Jerry D. Hogan, Beaumont, Tex.

Application June 15, 1936, Serial No. 85,206

3 Claims. (Cl. 223—69)

This invention relates to a garment stretcher of a class embodying a plurality of frame members over which a garment is placed and held in a desired stretched position, particularly after 5 cleaning and during drying thereof. The invention is particularly adapted to drying of women's skirts of crocheted or knitted fabric and will be described as embodied in such device.

The invention contemplates and therefore has 10 as an object a skirt blocker for stretching a garment longitudinally and transversely and holding the stretched garment in such blocked condition that after removing the garment it will have the desired shape.

15 A further object of the invention is the provision of a simple and inexpensive device that is foldable into a small space when not in use and adapted for use by the average woman in the home.

20 The objects of the invention are obtained by providing suitably contoured side bars to apply transverse tension on the garment to be blocked. End bars are suitably secured to the side bars to hold such side bars in spaced relation and to 25 provide means for longitudinally tensioning the garment being blocked. The desirable contour of a garment, for example a skirt, is not obtained when placed upon a blocker that holds the garment edges in a straight line. I therefore provide 30 suitable contour of the end members to conform with the contour of the article being stretched. Fasteners are then provided upon the end members so that the garment may be easily attached to maintain the desired shape. A 35 construction within the purview of the invention is hereafter more fully described and illustrated in the drawing, in which:

Fig. 1 is a plan view of an embodiment of my invention.

40 Fig. 2 is a side view of the embodiment shown in Fig. 1.

Fig. 3 is a sectional view taken on line 3—3 of Fig. 1.

Fig. 4 is a sectional view taken on line 4—4 of 45 Fig. 2.

1, 2 are side members and 3, 4 are end members which are assembled to form a generally rectangular device. The upper and lower ends of the side members are reduced in sections as 50 shown at 7 and 8 in Fig. 2. The outer edges of said side members are, however, rounded, as shown at 10 in Fig. 4, and this contour is maintained throughout the reduced sections 7, 8.

The ends of these members are slotted to facilitate 55 adjustment and assembly. The upper

ends of the members are slotted as shown at 5. The slot at the lower end, 6, terminates short of the end of the member and is provided with suitable graduation 9 whereby proper adjustment is facilitated.

5 The ends of the member 3 are centrally grooved to a depth shown by dotted line 11 to receive the reduced end 7 of the side member. The lower edge 12 is contoured to be suitable for stretching a garment of a given type. For example, if a 10 skirt is to be stretched, a suitable arcuate contour is given edge 12, as shown, to conform with the waistband when the garment is in a flat stretched condition. Slots 13, which are generally parallel with edge 12, are provided to facilitate 15 adjustment.

End member 4, similar to end member 3, has its ends centrally grooved as shown at 19 in Fig. 3, the grooves terminating as shown by dotted lines 14 in Fig. 1. This end member is 20 also provided with a suitable contoured upper edge 15 to conform with the desired shape of the edge of the garment to be stretched. Again, if the article to be stretched is a skirt, a suitable arcuate curve is provided. The radius of 25 curvature in such instance would approximate that of edge 12 but would provide a concave edge, whereas the edge of the member 3 is convex. The ends of the member 4 are also slotted as shown at 20, the slots being generally parallel 30 to edge 15.

Edges 12 and 15 are provided with fasteners 16. Any suitable fasteners may be used instead of hooks 16 as shown. Two rows of fasteners are provided in order that attachment to the 35 garment may be made at frequent intervals throughout its circumference. These fasteners are located at regularly spaced intervals and also serve as a scale for suitable transverse adjustment of the blocker.

40 The stretcher members are secured together by any suitable means such as bolts 17 provided with wing nuts 18. By merely loosening the wing nuts on the bolts 17 the blocker may be readily adjusted, measurements being marked 45 along the hooks 16 from the center to the ends of the top and bottom bars to correspond with the graduations 9 on the side bars. Or, member 3 may readily be removed by virtue of the open slots 5. Member 4 may be readily detached 50 from side members 3, 4 by removing the bolts from slots 6. The device can be thus readily stored in a small space when not in use.

The construction employed is capable of a certain range of change and modification without 55

a material departure from the spirit of the invention, and I do not limit myself to the specific structure disclosed except as hereinafter claimed.

What is claimed is as follows:

5 1. A garment form comprising a pair of side members having slots in their opposite ends, a pair of end members having their ends bifurcated to receive and adjustably connect said side members in variously spaced relation, said end members having their opposed edges arcuate and means for securing the garment edges to the arcuate faces of the end members.

10 2. A garment form comprising a pair of side bars adapted to receive a garment to be stretched, an upper end member adjustably connected to the upper ends of said side bars, said member having its lower edge convex, a lower

end member adjustably connected to the lower ends of said side members and having its upper edge concave and means on the opposed curved edges of said members and adjacent the opposite faces thereof for securing a garment thereto with the opposite sides of the garment in parallel planes.

15 3. A skirt stretcher including a pair of side members, and a pair of end members, means to connect the end members and said side members together for adjustment both laterally and longitudinally, the adjacent sides of said end members being curved downwardly, and means on said curved sides of said end members to secure the upper and lower ends of a skirt thereto.
